UNITED STATES PATENT OFFICE.

WILLIAM R. JOOSS, OF CLEVELAND, OHIO.

COMBINATION-TOOL.

1,321,312.

Specification of Letters Patent.

Patented Nov. 11, 1919.

Application filed June 15, 1918. Serial No. 240,169.

To all whom it may concern:

Be it known that I, WILLIAM R. JOOSS, a citizen of the United States, residing at Cleveland, in the county of Cuyahoga and 5 State of Ohio, have invented a certain new and useful Improvement in Combination-Tools, of which the following is a full, clear, and exact description.

This invention relates to a combination 10 tool which is more particularly designed for the purpose of making measurements, and in certain respects is the equivalent of a trammel, although it has other functions in addition to those mentioned.

15 The object of the invention is to provide a combination tool which may be used for a variety of purposes.

Generally speaking, the invention may be said to comprise the elements and combinations thereof as set forth in the accompanying 20 claims.

Reference should be had to the accompanying drawings forming a part of this specification in which Figure 1 is an elevation of the device; Fig. 2 is a top plan view; Fig. 3 is a bottom plan view; Fig. 4 is an elevation showing in more detail a portion of the construction; Fig. 5 is a sectional elevation through a portion of the tool; Fig. 6 25 is a sectional elevation through another portion of the tool; Fig. 7 is a transverse section through a portion of the tool; Fig. 8 is an elevation more or less diagrammatic in character, showing certain of the implements forming a part of the tool; Fig. 9 is a side elevation of the construction shown in Fig. 8; Fig. 10 is a side elevation with portions in section of an implement for use in connection with the tool; Fig. 11 is an elevation of 30 an implement used in connection with the tool; Fig. 12 is an elevation with portions in section of an implement adapted for use in connection with the tool; and Fig. 13 is an elevation of the implement shown in Fig. 12.

45 The device comprises a straight edge member which is indicated at 1. In order to adapt the tool for various uses, this member 1 is provided with graduations in inches and fractions thereof, the fractions into which 50 the inches are divided being varied so as to provide a plurality of scales measuring in eighths, sixteenths, thirty-seconds and sixty-fourths of an inch. Obviously the particular 55 graduations mentioned are not in any sense limiting, as the scales having other degrees of graduation may be used with equal fa-

cility. The straight edge 1, upon one side thereof, is provided with a groove 2, which extends longitudinally of the straight edge. This groove is preferably located at substantially the center of the member 1.

60 Secured at one end of the straight edge is a fixture 3, this being immovable when once mounted upon the straight edge, and is secured to the straight edge in a manner which 65 will be subsequently described.

There is also a movable element or member 4 which has a part that engages with the groove 2 so that as the member 4 is moved along the member 1 it is guided by an edge 70 of the member 1 and in part by the groove 2. The member 4 is provided with means by which when moved to any adjusted position upon the member 1 it may be clamped and held in its adjusted position.

75 The member 4 is provided with a part 5 which has a cylindrical opening therein in which is located a movable member 6. This member is notched out as indicated at 7 and has an extending part 8 upon which there is 80 an inwardly extending foot 9. This foot is adapted to engage with the groove 2 of the straight edge 1, and an edge of the member 1 extends within the notched-out portion of the member 6.

85 The member 4 is slotted as indicated at 10 in Fig. 7, which slot receives the member 1.

The member 6 at its upper end is provided with a screw-threaded shank 6^a, which in turn is engaged by a nut 11. This nut is 90 hollowed out and within the hollowed-out portion is a spring 12 which bears against the top of the part 5. When the nut 11 is tightened it draws the member 6 upward and so holds the member 1 against the upper 95 portion of the slot 10, thus preventing any sliding movement between the member 1 and the part 4.

100 The member 4 also has an extending part 13 which is provided with a cylindrical opening that receives a member 14. This member 14 at its outer end is provided with a threaded extension 14^a, and upon the extension 14^a is a nut 15, which bears upon the outer end of the part 13. The nut 15 is provided with a recess in which is seated a spring 16 that bears upon the outer end of the part 13.

105 The member 14 is formed in the body thereof with a half-round groove 17, and 110 this cooperates with a half-round groove 18 which is formed in the body of the part 4.

When the half-round groove 17 of the member 14 is in registry with the half-round groove 18 it will be possible to pass through the registered grooves a shank 19, which 5 shank may form a part of a suitable implement to be used in connection with the tool as will be subsequently described. When such a shank has been inserted, and the nut 15 tightened, it draws the member 14 and 10 so wedges the shank 19 to hold it in its adjusted position with respect to the member 4.

The member 4 has upon one face thereof a recessed portion, as indicated at 4^b in Fig. 4. This recessed portion has an edge 4^c, 15 which edge is in the same plane as the axis of the shank 19. The edge 4^c is in contact with the straight edge 1 and may be moved in proximity to the scale graduations on the straight edge 1, so that by reading the position of the edge 4^c with respect to the scale 20 on the member 1, it indicates the position of the axis of the shank 19 of an implement used in connection with a tool.

The member 4 also has a part 13 through 25 which there is formed a cylindrical opening which is adapted to receive the shank 19 of an implement as has before been indicated. Extending transversely with respect to the opening in the part 13 is the part 14.

30 At the lower end of the part 13 there is a notch as indicated at 21^a which is adapted to receive a projection 25 which is formed of a part of the implement 26, the shank of which is indicated at 19. This projection 35 and notch construction is for the purpose of definitely locating the implement with respect of the member 4 of the tool and prevent any rotation thereof.

It will be noted by referring to Fig. 7, 40 that the member 14 in its normal position does not engage with the member 1 but stops short of such engagement so that the member 1 is permitted to move with respect to the member 4 and slide along the same.

45 The member 3 is in its general construction the same as member 4 with the exception that the member 24, which corresponds in function to the part 14 heretofore described, extends beyond the slot 25 in the 50 member 3, which slot corresponds to the slot 10 of Fig. 7, and forms an abutment against which the end of the member 1 is adapted to engage and be positioned as indicated at 26 in Fig. 3. The end of the member 1 55 as it abuts against the part 24 of member 3 is in the same plane as the axis in the shank 19^a which is the shank of the implement coöperating with the member 3. This is indicated at 27 in Fig. 1. Therefore the 60 center of the shank 19^a is at zero or the end of the scale of the member 1. It will therefore be clear that the distance measured on the scale by the edge 4^c as shown in Fig. 4 indicates the distance between the axes of the 65 shanks 19 and 19^a as shown in Fig. 1.

In connection with the shanks such as illustrated at 19 and 19^a, various implements may be used. For instance, as shown in Fig. 11, the shank which is indicated at 19^b may be provided with a pointed end as 70 indicated at 28, in which event the tool may be utilized as a marking tool producing parallel lines, the distance between which can be definitely measured upon the scale of the member 1.

75 Or the implements used, may be such as indicated in Fig. 8, in which the shanks 19^c are provided with head members 29 that have an edge 30, which edge is in line with the axis of the shank 19^c. These particular 80 implements such as shown in Fig. 8, are convenient for measuring inside diameters, and the distance between the edges 30 as shown in Fig. 8 may be correctly read upon the scale of the member 1.

85 The particular arrangement of these implements as shown in Fig. 8 is intended for measuring interior diameters or interior distances, while with the arrangement of the same implements as shown in Fig. 1, in 90 which the edges 30 are toward each other instead of away from each other, the tool may be used for measuring exterior diameter or distances.

95 As a modification of the particular implements shown in Fig. 8, there is shown in Fig. 10 a modified form in which the shank 19^d is provided at the head portion with a roller 31, the surface of the roller being in line with the axis of the shank 19^d. The use 100 of the implement shown in Fig. 10 is the same as the implement shown in Fig. 8, the difference being merely that the part which contacts with the object being measured provides a rolling contact instead of a non- 105 rolling contact, the rolling contact being preferable particularly in measuring objects with a roughened surface.

110 In Figs. 12 and 13 there is shown what is provided with a shank 19^e which at its lower end is recessed, as indicated at 32, and the outer shell of the recess is slotted, as indicated at 33. The recess 32 is adapted to receive a pointed needle-like member 34. 115 The outer surface of the split shell is tapered and receives a ball 35 which is provided with a tapered threaded opening. It will be clear that when the ball 35 is turned upon the threads of the shell which holds the part 120 34, it will compress the same against the pin 34 and hold it in adjusted position.

125 The various implements which have been described, are all provided with shanks which make them suitable for use in connection with the parts 3 and 4 of the tool as shown in Fig. 1, and by the substitution of the various implements described, the tool may be employed for the various measuring purposes which have been indicated.

Having described my invention, I claim:

1. In a tool of the character described, the combination with a straight edge member, of a member mounted thereon at one end of the straight edge, said member having means for securing the member to the straight edge, said member also having a part with an opening therein, an implement shank extending through said opening, means for securing the implement shank in the opening, a slidable member mounted upon the said straight edge, means carried by the slidable member adapted to engage with a portion of the straight edge to hold the said slidable member in adjusted position upon the straight edge, said slidable member being provided with an opening, a tool shank extending through said opening, and means for securing the tool shank in the said opening.

2. In a tool of the character described, the combination of a graduated straight edge having a longitudinal groove therein, a fixed member provided with a slot into which the said straight edge extends, a stop carried by the said fixed member against which the straight edge abuts, means carried by the said fixed member including a part which engages in the slot of the straight edge whereby the fixed member may be secured to the straight edge, a slidable member located upon the straight edge, said slidable member being provided with a slot adapted to receive the straight edge, said slidable member having a moving part provided with means which engages with the slot in the straight edge, and means for tightening the said slidable member to hold the slidable member in adjusted position, both the fixed member and the slidable member being provided with openings, implement shanks extending through said openings, and means for securing the said implement shanks in their respective openings.

3. In a tool of the character described, the combination with a graduated straight edge, of a fixed member at one end thereof, means for securing said fixed member upon the straight edge, said fixed member being provided with an opening, the axis of said opening being in line with the end of a straight edge, an implement shank extending through said opening, means for securing said implement shank in the opening, a slidable member mounted upon the straight edge, means associated with the slidable member for securing the same in fixed position upon the straight edge, said slidable member having an opening, an implement shank extending through said opening, means for securing the said shank in the opening, said slidable member being provided with a recessed portion having an edge in substantial contact with the side of a straight edge, the edge of said opening

being in the same plane as the axis of the opening which receives the shank of the implement.

4. In a tool of the character described, the combination with a straight edge, of a fixed member located at one end of the straight edge, said fixed member being provided with an opening, a shank of an implement extending through said opening, means for securing the shank in the opening, a stop member associated with the fixed member against which the end of the straight edge abuts, said stop member being so positioned that the end of the straight edge is in the same plane as the axis of the shank of the implement, a movable member upon the straight edge, said movable member being provided with a slot to receive the straight edge, said movable member having an opening, a slidable member in said opening, said slidable member having a foot adapted to engage in the slot in the straight edge, a nut for engaging the said slidable member to tighten the same, thereby to secure the said slidable member in adjusted position upon the straight edge, said slidable member being provided with an opening, an implement shank extending through said opening, means for securing the implement shank in the opening, said slidable member being provided with a recessed portion having an edge which is adjacent the straight edge, the edge of said recess lying in the same plane as the axis of the implement shank.

5. In a tool of the character described, the combination with a straight edge, a fixed member associated with the straight edge at one end thereof said fixed member having an opening, a second opening extending at substantially right angles to the first mentioned opening, a slidable member in the last mentioned opening, said slidable member being provided with a groove which coöperates with the first mentioned opening in the fixed member, an implement shank adapted to extend through the first mentioned opening in the fixed member, means for moving the said sliding member thereby to hold the shank of the implement against movement, a slidable member located upon the said straight edge, said slidable member being provided with an opening, an implement shank extending through the opening, a second opening in the slidable member extending at substantially right angles to the first mentioned opening, a movable member in said second opening, said movable member being provided with a groove which coöperates with the first mentioned opening, said shank extending through the groove in the said slidable member, and means for moving the slidable member to lock the shank against movement.

6. In a tool of the character described, the combination with a member adapted to be

mounted upon a straight edge, said member being provided with an opening, a second opening extending at substantially right angles to the first opening and in part intersecting the first opening, a tool shank in the first-mentioned opening, a slidable member in the second-mentioned opening, said slidable member being provided with a groove which coöperates with the first-mentioned groove, the groove in the slidable member coöperating with a portion of the implement shank, a nut for moving the said slidable member thereby to hold the shank of the implement against movement.

15 7. In a tool of the character described, the combination with a straight edge having a

slot formed therein, of a member adapted to be mounted upon said straight edge, said member being provided with a slot into which the straight edge extends, said member being provided with an opening, a slideable part in said opening, said slideable part having an extension with a foot thereon which is adapted to extend into the slot in the straight edge, a nut engaging said movable member, said nut when tightened moving the slideable member to hold the straight edge and the member against relative movement.

In testimony whereof, I hereunto affix my signature.

WILLIAM R. JOOSS.
